UNITED STATES PATENT OFFICE.

CARL O. ELLIS, OF TACOMA, WASHINGTON.

COLOR MEDIUM.

1,298,917.

Specification of Letters Patent.

Patented Apr. 1, 1919.

Application filed March 26, 1918. Serial No. 225,128.

To all whom it may concern:

Be it known that I, CARL O. ELLIS, citizen of the United States, residing at Tacoma, in the county of Pierce and State of Washington, have invented a certain new and useful Improvement in Color Mediums, of which the following is a specification.

My invention relates to improvements in color mediums that are adapted for use 10 in the operation of producing color effects upon objects disposed upon the stage of a theater, and the object of my invention is to provide a color medium of simple form of construction and which shall embody a 15 plurality of small removable sections of colored glass so that when one of such sections is broken it may be replaced without renewing the entire color medium.

Further objects reside in the form of construction of the color medium and in the use of a centrally arranged cross-bar which strengthens the frame and enables small sections of glass to be used and at the same time does not cast any appreciable shadow 25 when the light from a lamp is caused to pass through the color medium.

In theaters it is customary to use color mediums for the purpose of casting colored light on any desired object on the stage. 30 These color mediums as ordinarily used are simply transparent colored plates that are formed of some non-breakable gelatinous substance and are adapted to be held in front of a lamp or other source of light so that 35 the rays of light from the lamp will be caused to pass through the color medium before they fall upon the objects toward which they are directed and will thereby produce a coloring effect on the objects.

Obviously, separate color mediums or plates will be required for different colors that are to be thrown on the stage.

The use of colored glass in the construction of color mediums is ordinarily unsatisfactory for the reason that they are handled a great deal and are very liable to be broken thus making them comparatively unreliable and expensive.

My invention overcomes both of these objectionable features by providing a glass color medium that is constructed of a plurality of small sections of glass placed in a frame from which they are easily removable so that when one section of the glass 55 is broken the utility of the entire color medium is not destroyed and the broken section

may be quickly and easily replaced by a new section.

In the accompanying drawings Figure 1 is a view in elevation illustrating color mediums constructed in accordance with my invention;

Fig. 2 is a view in cross-section on broken line 2, 2 of Fig. 1;

Fig. 3 is an enlarged fragmentary view 65 in cross-section on broken line 3, 3 of Fig. 1;

Fig. 4 is a view in elevation illustrating a circular color medium constructed in accordance with my invention, and

Fig. 5 is a view in cross-section on broken 70 line 5, 5 of Fig. 4.

Referring to the drawings, throughout which like reference numerals designate like parts, the numerals 6 and 7 designate the two sides and 8 and 9 the two ends of a 75 rectangular frame that is constructed in accordance with my invention and is provided with a longitudinally extending medially disposed bar 10 which is parallel with the side members 6 and 7 and divides the frame 80 into two halves.

The side members 6 and 7 and the medial bar 10 are each grooved in a well known manner, as indicated at 11 for the reception of the ends of glass color medium sections 12 that are adapted to slide vertically 85 within the grooves 11.

The lower end bar 8 of the frame is grooved in a similar manner for the reception of the side edges of the lowermost sections 12 of glass.

The upper frame bar 9 is of less thickness than the remaining parts of the frame so that one of its sides is flush with one side wall of the grooves 11 as more clearly shown 95 in Fig. 3, thus leaving the upper ends of the grooves open, and the uppermost sections 12 of glass are held in position by removable cleats 13 that are provided on one edge with notches 14 and are adapted to be 100 secured to the frame bar 9 by screws 15.

From the above description taken in connection with the drawings, it will be apparent that when the cleats 13 are removed the sections 12 of colored glass may be freely 105 inserted in or removed from the grooves 11.

When a sectional color medium constructed in this manner is struck hard enough to break the glass, usually only one or two of the sections 12 will be broken and such 110 sections can easily and quickly be replaced with new ones by removing the cleats 13.

If one of the sections 12, toward the central portion of the color medium, is broken while the device is in use the fragments of broken glass may be removed from the 5 grooves 11 and the sections above may be allowed to move downwardly to form a solid central portion through which light may be projected and to leave an opening at the top of the color medium which does not seriously 10 impair its utility and which may be filled by a new section of glass at the convenience of the operator.

It will thus be seen that the breaking of one or two central sections does not render 15 the entire device inoperative and that the broken sections may be removed at a very small cost.

Where rectangularly shaped color mediums are used they are preferably slidably 20 mounted, one above another in a grooved frame 16, as shown in Figs. 1 and 2, each of the color mediums being of a different color and being adapted to be moved into a position in front of a lamp 17 so that the 25 rays of the lamp may be projected therethrough.

The use of the central frame bar 10 makes it possible to construct a practical color medium out of small sections of glass and it 30 has been found by experiment that when the device is thus constructed and is used in connection with a lamp as illustrated in Fig. 2, the rays of light are so deflected and diffused by the colored glass that no appreciable 35 shadow is cast by the centrally disposed frame bar 10.

In Figs. 4 and 5 I have illustrated a circular color medium constructed in accordance with my invention, this circular color 40 medium comprises a circular frame 20 having a diametrically arranged bar 21, the edges of the frame 20 and bar 21 being grooved for the reception of the edges of glass sections 22 that correspond to the sections 12.

In this circular form of construction I have provided cleats 23 that correspond to the cleats 13 and necessarily extend half way around the frame to permit the insertion of 50 the longest section 22.

The circular color mediums are not adapted to move in guides but when in use are held in front of a lamp so that light rays will be projected through them.

55 Manifestly, changes may be made in the forms, dimensions and arrangement of parts of my invention without departing from the spirit thereof.

What I claim is:

60 1. A color medium of the class described including an open frame provided with a central bar having a longitudinal groove in

each of the opposite side edges thereof, and a plurality of sections of colored glass having their outer ends detachably mounted in 65 said frame from end to end thereof at each side of said bar with their adjacent edges in contacting relation, said glass sections having their inner ends slidably removably positioned in the grooves of said central bar. 70

2. A color medium of the class described comprising an open internally grooved frame, a bar provided with longitudinal grooves in the opposite side edges thereof and extending across the medial portion of 75 said frame, a plurality of sections of colored glass having their adjacent edges in contacting relation and their ends slidably positioned in the grooves of said frame and said bar, and means to removably hold said glass 80 sections in position.

3. A color medium of the class described comprising an open frame internally grooved on two side portions and one end portion, the other end portion of the frame being thinner than the remainder of said frame so that one side face thereof is disposed in the same plane as one side wall of said grooves whereby 90 said grooves are left open at said other end portion of the frame, a plurality of sections of colored glass having their ends slidably fitted within said frame grooves with their adjacent edges in contacting relation, and a cleat removably secured to said thinner end portion of the frame to secure said 95 glass sections within the grooves of said frame and to allow said glass sections to be successively slidably inserted in or removed from said grooves.

4. A color medium of the class described 100 including an open frame internally grooved on two side portions and one end portion, the other end portion of the frame being thinner than the remainder of said frame so that one side face thereof is disposed in 105 the same plane as one side wall of said grooves, whereby said grooves are left open at said other end portion of the frame, a central bar within said frame having a longitudinal groove in each of the opposite 110 side edges thereof, a plurality of sections of colored glass having their ends slidably fitted within said grooves of the frame and the bar with their adjacent edges in contacting relation, and a pair of cleats removably secured to said thinner end portion of the frame to secure said glass sections within the grooves of said frame and said bar and to allow said glass sections to be successively 115 slidably inserted in or removed from said 120 grooves.

In witness whereof, I hereto subscribe my name this 16th day of March A. D. 1918.

CARL O. ELLIS.
